[57] ABSTRACT

End closure assemblies for sealing drums and containers include an inner seal for containing fluid pressure acting in the drum or shipping container which is adhesively set or connected between the rounded bead

about the end opening of the drum and the mating contoured flange on an end closure for the drum, and an outer seal of heat shrinkable material adhesively affixed about the rounded end of the drum and its mating end closure and operative to set the inner seal in assembled position when heated and cooled, the inner seal preferably embodying means for trapping pressure fluid acting in the drum.

Additionally, improved lighter gauge closure rings for use about said end closure assemblies where the fluid pressures acting in the drum exceeds the range that can be safely contained by the heat shrinkable outer seal materials, the improved closure rings and outer seal providing better frictional engagement between the coacting surfaces of the closure ring and the outer seal in assembled position than the metal on metal seals of the prior art devices.

The closure rings disclosed are lengths of relatively light gauge material and will include overlapping sections of varying lengths and either means to adhesively hold the closure rings in assembled position and/or means to lock the closure ring in assembled position. These improved closure rings may be utilized in end closure assemblies of the prior art type or in end closure assemblies having an inner seal in accordance with the present disclosure.

END CLOSURE ASSEMBLIES FOR CONTAINERS AND IMPROVED CLOSING RINGS THEREFOR

BACKGROUND OF THE INVENTION

This invention relates generally to metal, fiber and the like shipping and storage drums and containers, transformer cases, etc., having at least one end closure assembly securely connected to the container wherein the end closure assembly or assemblies, as the case may be, for such drums or containers are required by law to meet certain drop and hydrostatic tests to insure the safety of the container and its contents during storage, shipment or use and more particularly to an improved end closure assembly for such drums or containers designed to meet all such required tests but adapted more specifically for present day production line speeds.

The methods and means for closing metal and fiber shipping and storage containers have not been substantially improved in over 40 years and are being found increasingly unsatisfactory for today's more dangerous commodities.

The known prior art end closure assemblies for drums, generally include a steel closure ring which clamps a compressible gasket; made typically of; sponge rubber, tubular "neoprene," solid plastic materials or cellulose wadding, between the rounded end of the container and a matching annular peripheral member of flange on the end closure for the container such as is shown in U.S. Pat. Nos. 2,968,508; 2,447,825; and 2,226,396.

In order for these prior art closures to be effective, the compressible gasket must be compressed into place as the closure ring is clamped in assembled position about the end closure elements for a given container.

End closure assemblies utilizing these prior art closure rings which are generally V-shaped or semi-circular in cross-section have been found to have a number of important shortcomings in view of the tests required under the existing law. These may be broadly classified into problems relating to the compressible gasket materials and problems relating to the closure rings.

For example, it is well known that gasket material is effective over only a portion of the total recovery of the gasket material to size after it has been compressed. Thus, sponge gaskets are effective for a maximum recovery of about an eighth of an inch and harder gaskets such as solid "neoprene" for an even lesser amount.

In prior art end closure assemblies for containers to prevent leakage after fluid pressure is exerted on such end closure assemblies either during tests or during conditions which cause an increase in pressure in the containers, it is necessary for the gasket material to recover sufficiently during such periods so as to continue to exert some residual sealing action between the end curl of the drum and the mating annular flange on the end closure for the drum.

Thus, if the end closure assembly is expanded due to fluid pressure acting within the container for any reason and it lifts the end closure at any point beyond this factor of partial recovery for the given compressed gasket leakage will result and security of the container will be impaired.

To further impair or limit this recovery function of the compressed gasket material, it is known that the compressed gasket materials of the prior art closures will take a set when held compressed for a long period

of time. In order to meet this problem it is necessary to tighten the closure ring from time to time beyond the initial settings in order to maintain compliance with the tests required by the law. As a practical matter this usually is not done. Thus, a dangerous condition is established and allowed to continue with the passage of time.

Still, further, it is known that the speed with which compressed gasket materials recover is not instantaneous but is comparatively sluggish. Thus, when an end closure is lifted or separated from the rounded end of the container rapidly as by hydrostatic pressure applied by tests or by internal pressure caused by shock in shipment, leakage occurs during the recovery time required for the gasket material to recover or expand to effect sealing once again.

And last, pressure exerted by the end closure assembly on the gasket material has an equal force or pressure reaction being exerted by the gasket on the associated elements of the end closure assembly which is continually acting to lift the cover or end closure after the same is assembled to the drum or container. Thus, when hydrostatic pressure tests are made or internal pressure is developed in the container due to internal generation of pressure from chemical reaction of the material, from dents, or from thermal expansion, the force exerted by the compressed gasket material is acting in the same direction as the internal pressure and helps to overcome the restraint exerted by the closure ring. The compressible gasket thus tends to aid and abet other forces and pressures which cause leakage of the end closure assembly.

The prior art closure rings have met the above problems of the compressible gasket material in the conventional end closure assemblies by providing heavier and thicker gauge rings. For regulated products, that is dangerous materials, not only is a heavy 12 gauge steel closure ring used but additionally heavy forged lugs are applied which must be arc welded by hand to these closure rings to position them for receipt of a heavy and expensive locking bolt. In this regard, reference is made to Interstate Commerce Commission Regulation 17H and Department of Transportation Regulations and the abovementioned prior art patents.

The majority of these commercially available closure rings used in the prior art end closure assemblies are generally transversely split so that such rings can be assembled about an end closure assembly in which position the ends of the closure ring formed by the transverse split approach each other in butt type fashion. Due to variations in gasket material used in prior art end closure assemblies, variations in the amount of recovery afforded by each particular gasket material, and variations in the bead or end curl about the opening of the drum or container, such prior art closure rings must be dimensioned in contour and length so that the butting ends will not be brought into engagement with each other during assembly. To pass the required tests the end closure assembly for a given drum must be carefully fitted with a ring having a gap between the butted ends in a range between $\frac{1}{8}$ inch to $\frac{3}{8}$ inch. A larger gap will cause the end closure assembly to fail during test or usage because the cover or end closure will cease at the point of gap on the closure ring and leakage will result. Thus, each manufacturer's particular combination of drum bead or end curl, gasket material, mating cover and closure ring must be fitted very exactly both in contour and length to provide end closure assemblies

in accordance with the known prior art devices which meet the exacting requirements of the applicable regulations of the Interstate Commerce Commission and the Department of Transportation.

Although the manufacturers of drums or containers with such prior art end closure assemblies take great pains to accomplish this result, in practice, manufacturer's customers, that is, the fillers of the storage drums and shipping containers remove covers and rings and stack them indiscriminately. Thus, today there is no assurance and generally no effort made to match the rings to the mating covers and drums because this requires time, attention and effort. While this might have been done very satisfactorily at production line speeds prevalent many years ago for which such closure rings were designed, today's high speed production lines do not permit or allow for the necessary time required to properly assemble the optimum combinations of elements for each end cover assembly.

It is commonplace that the drums of one manufacturer are regularly assembled with closure rings intended for another manufacturer's drums so that even though each manufacturer may have taken painstaking care to produce drums with end closure assemblies thereon designed to pass the prescribed tests for dangerous materials required by law, such dangerous materials are in actual fact regularly shipped in containers that would not pass the required tests and present a continuing and even dangerous hazard to property and to persons who come in contact with such containers.

For the same reasons given above, compounded, reconditioners of steel and fiber containers are constantly under fire from the U.S. Government Agencies such as the Interstate Commerce Commission and the Department of Transportation for the failure of their reconditioned containers and drums to meet test requirements particularly in the case of dangerous products.

Further, the heavy forged lugs are disposed on the adjacent butted ends of the prior art closure rings. One is drilled and the other is tapped for a heavy $\frac{5}{8}$ inch threaded bolt. To allow play for starting the threaded bolt the drilled lug will be provided with an oversized hole. To compensate for this extra clearance a jam nut is provided to bring the bolt into tight engagement therewith. In order to expedite assembly the bolt will be made longer to facilitate threading the same into assembled position.

However, the oversized threaded lug reduces rigidity of the end closure assembly and the over-length bolt is a hazard to personnel because of serious accidents which result due to the catching thereon of gloves and trousers of the workers filling and assembling such containers.

Additionally, the $\frac{5}{8}$ inch bolt prescribed has a hex head to which power tools are applied. In order to utilize such tools suitable clearance must be provided. This results in the lugs being designed so that the bolt receiving eyes on the lugs are far enough away from the drum in assembled position to provide the necessary clearance for the power tools. To prevent bending of the closure ring during drop tests, it was desirable to have the bolt as close to the ring and the drum as possible.

All of this structure, i.e., the heavy gauge steel used for the closure rings; heavy forged lugs are welded by hand thereto; the drilled and tapped bolt receiving

openings on the lugs and the heavy bolt and locknut result in a cumbersome heavy expensive uneconomical closure ring. Additionally, starting of the thread, detaining the locknut as the bolt is tightened into the threaded lug; and tightening of the lock nut are labor-consuming operations which often are not performed properly at today's production line speeds so that improper assembly results and unsafe containers are used for storing and shipping of many dangerous products.

Thus, end closure assemblies for storage and shipping containers which include, a compressible gasket and a closure ring formed to cause compression of the gasket, perform unsatisfactorily for the dangerous products shipped in such drums and containers today because they are not capable of being assembled properly at today's production line speeds; are generally not interchangeable on end closure assemblies for shipping and storage containers of other manufacturers; require re-tightening when such end closure assemblies are used over extended periods of time; are effective only for a portion of the recovery of the compressible gasket; and require heavy gauge steel special fitted closure rings that are expensive to manufacture if the end closure is to meet the requirements of the law.

End closure assemblies for drums and containers in accordance with the present invention overcome these shortcomings of the prior art devices by altering the structure of the end closure assembly to eliminate the use of a compression gasket means to effect sealing and utilizing in place thereof an inner seal between the bead or end curl of the container and the mating flange of the cover or end closure for the container designed to contain or trap fluid pressure in the container and to be adhesively affixed in assembled position by action of an outer seal which may be either an adhesively attached heat shrinkable plastic material alone; material together with a specially designed closure ring; or just one of the specially designed closure rings.

The specially designed closure rings are of relatively light gauge material and include overlapping ends, the over-lapping ends extending more or less depending on whether a specially designed locking assembly is utilized with the closure ring or not.

SUMMARY OF THE INVENTION

Thus, the present invention covers an improved end closure assembly for a container including, means forming a contoured end about the opening for said container, an end closure disposed to close said opening and having an annular flange contoured to mate with the contoured end of the container, an inner gasket means adhesively connected between the mating surfaces of the contoured end of the container and the inner wall of the contoured flange; said inner gasket means designed to form a chamber in assembled position having an annular opening in communication with the inside of the container, and heat shrinkable means adhesively connected about the end closure assembly adapted when heated and cooled to set the inner seal and to tightly seal the end closure assembly about the contoured end of the container.

Alternatively, the combination of an improved closure assembly as above defined wherein the closure ring is of the overlapping type.

The present invention also covers an improved overlapping closure ring for use in an end closure assembly as above defined having at least five annularly and con-

centric angled sections thereon forming a substantially hemi-hexagonal shape in cross-section, the inner most annular sections on opposite sides of said hemi-hexagonal closure ring being proportioned so that when the ring is in assembled position these inner annular sections may be crimped beyond the horizontal either manually or automatically in machines designed therefor.

Other important objects and advantageous features of my invention will be apparent from the following description wherein for purposes of illustration several specific embodiments of the invention are described and are shown in detail in the drawings wherein:

FIG. 1 is a side elevation of a fragment of a shipping container showing an end closure assembly in accordance with the present invention in assembled position on the drum and including one form of overlapping split type closure ring.

FIG. 2 is an enlarged cross-sectional view taken on line 2—2 of FIG. 1 showing a portion of the container and the end closure assembly thereon.

FIG. 3 is an enlarged front view of a fragment of the closure ring shown in FIG. 1 showing the associated lug members and threaded means in assembled position.

FIG. 4 is a perspective view of the overlapping section of the closure ring shown in FIG. 1.

FIG. 5 is a perspective view of a segment of the inner seal for the end closure assembly shown in FIG. 1.

FIG. 6 is an enlarged cross-sectional view of the end closure assembly shown in FIG. 1 without a closure ring.

FIG. 7 is an exploded partial perspective view of a fragment of one end of a shipping container, a tubular type inner seal with adhesive thereon, and the main annular portion of the end closure assembly for the shipping container.

FIG. 8 is a top view of a segment of the inner seal shown in FIG. 7 with adhesive means thereon.

FIG. 9 is an enlarged cross-sectional view of an end closure assembly in accordance with the invention utilizing the inner seal shown in FIG. 8, an outer seal of heat shrinkable plastic material and a closure ring crimp in assembled position.

FIG. 10 is an enlarged cross-sectional view of the end closure assembly shown in FIG. 9 subjected to sudden high internal pressure from the container.

FIG. 11 is a side elevation of a fragment of a shipping container showing another form of end closure assembly in accordance with the invention.

FIG. 12 is an enlarged cross-sectional view taken on line 12—12 of FIG. 11 showing a portion of the container and the end closure assembly thereon.

FIG. 13 is a perspective view of the closure ring utilized in the end closure assembly shown in FIG. 11.

FIG. 14 is a side elevation of a fragment of a shipping container showing still another form of end closure assembly in accordance with the invention.

FIG. 15 is an enlarged cross-sectional view taken on line 15—15 of FIG. 14 showing a portion of the container and the end closure assembly thereon.

FIGS. 16a and 16b are a perspective view of the closure ring and a side elevational view of the locking unit used in the end closure assembly shown in FIG. 14.

FIG. 17 is a cross-sectional view similar to FIG. 12 showing the locking means in open position.

FIG. 18 is a cross-sectional view similar to FIG. 12 showing the locking means in closed or locked position.

Referring to FIGS. 1 to 5 and FIG. 6 of the drawings, a container or drum generally designated 10 with an end closure or cover 11 is illustrated to show alternate forms of end closure assemblies in accordance with the present invention. For convenience, an end closure assembly with a closure ring will be described first by reference to FIGS. 1 to 5 and FIG. 6 illustrates the end closure assembly with the closure ring removed.

The container 10 may be any conventional type container such as a steel alloy or fiber container that will form a material receiving chamber generally designated 12 which will have at least one end opening as at 13. Containers or drums of this type are well known and easily purchaseable on the open market.

The container or drum 10 is provided with an annular bead or contoured section as at 14 which is formed about the end opening 13 of the material receiving chamber 12.

The cover or end closure 11 is received in the opening 13 of the material receiving chamber 12 and includes, a central portion 15 and an annular contoured flange 16 connected about the periphery of the central portion 15. The annular flange in cross-section will also have a contoured shape and will be sized to permit the end closure or cover 11 to overlie and mate with the annular bead 14 of the container in assembled position as is clearly shown in FIGS. 2 and 3 of the drawings.

Between the annular bead 14 and the annular flange 16 an inner seal 17 is provided, a fragment of which is shown at FIG. 5 of the drawings.

The inner seal 17 consists of a V-type gasket disposed in assembled position so that the opening for the V faces the interior of the container. This gasket will be made of any suitable chemically inert material adapted to resist any corrosive or erosive action by the material contained in the chamber 12 of the container 10. Inner seal 17 may be made of plastic materials such as poly-fluorocarbon resins, polyvinylchloride and polypropylene and such materials for these purposes are easily purchaseable on the open market.

In assembled position the V-shaped inner seal will be adhesively affixed as at 17a and 17b to the annular bead 14 and to the inner wall of the annular flange 17 of the cover member 11. The adhesive selected will of course also be resistant to chemical action.

When the end closure 11 is brought into fluid tight engagement with the annular bead 14, the inner seal will act to prevent leakage from the material receiving chamber 12 formed in the shipping container 10 because of the adhere connection and because of the V-type gasket from which the inner seal is formed which acts to trap or relieve fluid pressure acting in the chamber 12 of the container 10.

The end closure or cover 11 illustrated in FIGS. 1 to 6 of the drawings is of the type known as a fully removable drum head. It will be understood that this type cover or end closure may have an access opening departing from the scope of the present invention.

The end closure or cover 11 shown in FIGS. 1 to 5 is held in engagement with the open end 13 of the shipping container by an outer sealing tape 19 and a closure ring 20 which are disposed concentric to each other. The other sealing tape 19 being disposed in circumferential engagement with the annular bead 14 and annular flange 16 and the closure ring in turn being in circumferential engagement with the outer sealing tape on the side thereof remote from the annular bead 14 and

annular flange 16 as is clearly shown in FIGS. 1, 2 and 3 of the drawings.

The outer seal 19 will be made of high tensile strength plastic material such as polyfluorocarbon resin, polyvinylchloride and polypropylene and in the case of the outer sealing tape the material will be heat shrinkable, that is, material that shrinks when heated and cooled. The main direction of shrinking in accordance with the present invention being twice as much in its width as in the length of the material selected so that in assembled position the shrinkage of the outer sealing tape will cause the end closure or cover 11 to be pulled down tightly and thus the inner seal will be adhesively seated or connected in assembled position to the annular bead 14 and the inner wall of the annular flange 16. The degree of heating required will be that of a conventional gas burner flame operating in a range between 120°-200°F. Application of heat will be continued for about 3 to 5 minutes to bring the material up to temperature and then the end closure assembly can be permitted to be air cooled or can be cooled by any suitable technique such as quenching with water.

It will be understood by those skilled in the art that any heating and cooling technique applicable to produce the desired shrinking of the heat shrinkable outer sealing material may be utilized without departing from the scope of the present invention.

The heat shrinkable outer sealing tape 19 will be adhered to the outer surface of the drum, the annular bead 14, the annular flange 16 by any suitable adhesive which will resist chemical action and hold the outer sealing tape in assembled position to permit the heating and cooling thereof for achieving the desired seating of the V-shaped inner gasket to provide the FIG. 6 form of end closure assembly in accordance with the present invention.

This form of end closure is adapted to seal against fluid pressures acting in the chamber 12 of the container 10 in a range between 3-5 P.S.I.G.

Additionally, the outer heat shrinkable tapes or seals 17 may be reinforced with glass filaments or other types of fibers to increase the tensile strength of these materials.

Where the pressure however exceed the indicated range of 3-5 P.S.I.G. then it is necessary to reinforce the end closure assembly with a suitable closure ring which can be easily applied to the drum one form of which will now be described.

CLOSURE RING WITH OVERLAPPING ENDS AND LOCKING MEANS

Closure ring 20 is transversely split circumferential element having a main circumferential section 21 and an overlapping section 22 which is spot-welded to one end of the main section 21 so that in assembled position the overlapping section 22 will overlie the opposite or remote end 23 of the main circumferential section 21 as is shown in FIGS. 1, 2 and 3 of the drawings.

The overlapping section 22 may be a reformed part of the ring itself that is it may be a continuous section of the ring offset from the main circumferential section 21.

The circumstance of the closure ring 20 will be a function of the circumference of the end closure assembly of which it is part. Since the overlapping section 22 has a substantial length sufficient distance can be allowed between the end 24 of the main section 21 to

which the overlapping section 22 is connected and the opposite end 23 to avoid interference therebetween when the closure ring is locked into its assembled position.

In order to lock or clamp the closure ring 20 into its assembled position, a first locking lug 25 is formed integral with or connected as by welding to the end of the overlapping section remote from the end connected to or continuous with the main section 21 and a second locking lug 26 is connected by spot-welding medially along the main section 21 a predetermined space distance from the end 23 to permit the locking lugs to be operatively associated as by bolting the lugs together with a locking bolt generally designated 27 and more fully described below.

FIGS. 1, 2 and 3 show that the locking lugs 25 and 26 have a convoluted S-shape and will depend from the locking ring 20 substantially parallel to the longitudinal line of the container 10 for reasons which are well known to those skilled in the art.

At the end of the locking lugs remote from the ring there is formed a bolt receiving eye respectively at 29 on the locking lug 25 and 30 on the locking lug 26. The bolt receiving eye 29 and 30 will have substantially identical diameters. However receiving eye 30 will have an insert 31 fixedly mounted therein having a threaded bore 32 therethrough.

The locking bolt 27 is shaped to fit into the bolt receiving eye 29 and to engage the threaded bore 32 in the insert 31 so that when the locking bolt is threaded into the threaded bore 32 it will draw the locking lug 25 and 26 together and thus reduce the circumferential length of the closure ring and thus lock it into assembled position.

As is shown in FIG. 3, the locking bolt includes a locking head 35 which is bored as at 36 to receive a hex head wrench for tightening and loosening the locking bolt during assembly and disassembly of the closure ring 20. The head 35 is provided with a shoulder 37 which will engage one edge of the locking lug 25 when the shank portion 38 is fitted into the bolt receiving eye 29. The shank 38 is provided with a groove 39 in which an epoxy or other adhesive material will be inserted to help lock the shank portion 38 in assembled position. Projecting from the shank portion 38 in alignment with the threaded bore 32 is an elongated threaded section 40 sized and threaded to fit the threaded bore 32. The elongated section 40 includes, an extension section 41 as shown in FIG. 3 of the drawings. The extended section 41 is separated from the threaded section 40 by a groove as at 42 so that the extended section 41 may be snapped off or removed easily after the locking bolt 27 is in assembled position. The extension 41 will facilitate assembly of the locking bolt in the bolt receiving eyes 29 and 30 of the respecting locking lugs 25 and 26 and the length of the bolt with the extension will permit assembly of the closure ring with the bolt for shipment to the customer.

By further reference to FIGS. 1, 2 and 3, it will be noted that the closure ring 20 has five interrelated annular sections which in cross-section appear hemi-hexagonal in design. This annular design obviously differs from the round contoured ring which is known in the prior art. Additionally, however, it differs from the annular contoured ring in the prior art in that such rings have three sides whereas those disclosed herein have five sides.

In this five sided ring more fully described below, the two most radially inward annular section of this five sided ring are so proportioned that when the ring has been closed in place the respective short inner annular section will be angled below or inwardly of planes perpendicular to the longitudinal line of the container and therefore when forces act instantaneously or otherwise to force open the end closure assembly the forces brought to bear on the respective inner annular segments of the closure ring cause the closure ring to resist further lifting of the cover and thus the closure ring acts to hold the adhesively connected inner seal 17 in assembled position.

Thus, closure ring 20 is shown to include, a center section 45, spaced side sections as at 46 and 47 connected at one edge to opposite sides of the center section 45, a first clamping section 48 and a second clamping section 49 each respectively connected to the edge or side of the associated side section remote from the center section 45.

FIGS. 1, 2 and 3 show the clamping ring in assembled position and show that the respective clamping sections 48 and 49 are so sized and so positioned after they are crimped during assembly that they lie inwardly of parallel and spaced planes transverse or perpendicular to the longitudinal line of the container 10.

FIG. 4 shows that the overlapping section 22 has projecting ears at 50 and 51 with corresponding slots 52 and 53. The projecting ears can be bent into engagement with the cover and outer wall of the container and thus act in addition to the locking lugs 25 and 26 to strengthen and lock the closure ring at the transverse slit. Slots 52 and 53 provide means for inserting a screwdriver therethrough to facilitate releasing the closure ring from the end closure assembly when the locking bolt 27 opens or separates the closure ring from its assembled position on the end closure assembly for the container 10.

ASSEMBLY OF END CLOSURE

In the form of the invention above described, the assembly of the end closure elements is relatively simple. In that the inner seal member 17 can be adhesively connected to the inner wall of the annular flange 16 of the end cover before it is connected to the end closure assembly for the container 10.

When it is desired to place the end closure 11 into position to seal the end opening 13 of the container 10, a suitable adhesive will be applied either to the inner seal 17 or to the annular bead or contoured section 14 and the end closure 11 is then set into position as shown in FIGS. 1 and 2 of the drawings.

Depending on the pressures that will be generated in the container, the end closure may be sealed solely by the circumferentially disposed heat shrinkable tape or seal 19 which is wound about the main flange 16 and the annular bead 14 until it overlaps a substantial amount and is then heated and cooled and by shrinkage at least twice more in width than in length to exert the necessary pressure to set the inner seal 17 in assembled position, or by combing the heat shrinkable outer tape or seal 19 with a closure ring 20 which is assembled after the heating and cooling of the heat shrinkable outer tape to the end closure assembly in the manner above described.

OPERATION OF THE END CLOSURE ASSEMBLY

When fluid pressures within the drum from whatever cause act against the end closure assembly, it will tend to raise the end closure 11 from the annular bead 14. When this occurs the inner seal 17 and the heat shrinkable tape alone or in collaboration with the closure ring act to prevent leakage from the chamber 12 formed in the inner container 10.

10 This occurs because the inner seal receives the fluid pressure in side the trap or chamber 18 in communication with the open end of the V-shaped inner seal 17. This pressure will press the inner seal against the inner wall of the mating flange 16 on one side and the annular bead 14 on the other side and will set the adhesive connecting the inner seal in assembled position even more firmly. Similarly, the heat shrinkable outer tape or seal 19 which is adhesively connected in assembled position being of high tensile strength material and of sufficient thickness will tend to hold the end cover and the drum in assembled position thus resisting the force of the fluid pressure acting in the inner seal 17. Further, however, if a hemi-hexagonal closure ring as above described forms part of the end closure assembly the forces will tend to spread the spaced annular side pieces 46 and 47 away from each other. However, this action in turn will bring pressure to bear on the inner clamping sections 48 and 49 which due to their crimped position inwardly of the spaced parallel planes perpendicular or normal to the longitudinal line of the container will also resist further lifting of the end closure 11 from its assembled position on the cover.

25 In a severe case of impending rupture as in a drop test the outer sealing tape 19 and the closure ring 20 will act to hold the adhesively connected inner seal 17 in assembled position because this arrangement has greater frictional engagement than is obtainable by the known commercially available prior art end closure assemblies in which the closure ring is in engagement 30 with the metal cover and metal container or drum. The coefficient of friction for the metal closure ring 20 and the outer heat shrinkable tape or seal 19 is found to be in the order of 0.5 whereas that of metal on metal used in the prior art devices is 0.17. This increased coefficient of friction enhances the grip of the closure ring 20 in the end closure assemblies of the present invention and provides improved security therefore.

35 Thus, there is disclosed an end closure assembly having a combination of an inner V-shaped adhesively connected sealing material 17, an outer heat shrinkable sealing tape 19 and a specially shaped ring which is effective over a far greater distance of impending rupture than the recovery capacity of conventional compressible gaskets of the present known prior art end closure assemblies. The result is achieved by replacing the sealing arrangement of the prior art devices; which depend on the elasticity of the compressed sealing gasket; with an inner seal that is adhesively affixed and yields when fluid pressure is exerted but contains such fluid pressure within the seal.

ANOTHER FORM OF INNER SEAL

40 FIGS. 7, 8, 9 and 10 show another form of inner seal which can be utilized in the form of the invention shown in FIGS. 1 to 5 and FIG. 6 as above described.

45 This alternate inner seal generally designated 17a is a thin walled tubular plastic gasket which will be chem-

ically inert and resistance to any corrosive or erosive effect of the materials which may be contained in the drum. It will have an approximate thickness of 6 mils and a sufficiently large diameter so that in assembled position it will perform the desired gasketed function between the annular bead 14a about the end opening of the drum 10a and the annular flange 16a of the end cover 11a when no hydrostatic pressure is acting in the container as shown at FIG. 9 of the drawings and conversely will permit the cover to expand and form a 10 chamber or trap for fluid under pressure from the inside of the container without rupturing the seal between the annular bead 14a and the annular flange 16a when subjected to such pressure.

The tubular element thus can have a diameter in 15 range from a quarter inch to a half inch depending on the size of the annular bead of a given drum and the matching annular flange of its associated end cover.

In order to accomplish this desired result, the tubular inner seal 17a is adhesively affixed to the inner wall of the annular flange 16a and the surface of the annular bead 14a. Thus in assembly, the tubular inner seal 17a will be provided with a continuous bead of an adhesive material along one outer surface as shown at 17b and on the diametrically opposite outer surface a second continuous bead of adhesive will be affixed as shown at 17c. These adhesive beads will of course be made of a material which is chemically inert and will resist any corrosive effects from the materials which are contained in the drum 10a. The continuous bead of adhesive 17a will permit the tubular inner seal 17a to be first adhesively affixed to the inner wall of the annular flange 16a and when the annular flange 16a is assembled to its mating position with the annular bead 14a of the drum the pressure sensitive adhesive bead 17c at the diametrically opposite side will adhere to the annular bead of the drum so that in assembled position the tubular element will be flattened between these associated mating elements as is clearly shown in FIG. 9 of the drawings.

FIG. 9 further shows that the end closure assembly will include either the outer seal of heat shrinkable adhesively connected material 21a and/or an associated clamping ring 20a.

When the end closure assembly is subjected to internal pressure, hydrostatic tests or the cover is deformed due to drop tests or rough handling which would cause the cover to lift and thus move the annular flange 16a out of mating position with the annular bead 14a, that the tubular inner seal will not separate therefrom because of the adhesive holding it in assembled position but will invert on itself as shown in FIG. 10 to form a trap or chamber as at 17d which will be as strong as the V-packing because it presents double the thickness by reason of the inversion caused by the pressure fluid acting in the chamber 17d. A tubular inner seal of this type has some advantages over the V-type inner seal above described in that this tubing is cheaper to make and to apply than the V-type inner seal.

Further, this construction is completely distinguishable from the elastic type seals of the prior art which are thick walled tubular gaskets that depend for their sealing effectiveness on elastic properties and not on the deformation of the inner seal for accomplishing the desired sealing effect under conditions which cause high pressures to act either momentarily or otherwise in the container.

OVERLAPPED AND ADHERED CLOSURE RING

FIGS. 11, 12 and 13 show another form of the present invention in which an alternate closure ring is provided which is much thinner and much longer so that the closure ring can be applied by encirclement of the end closure elements of the end closure assembly for the drum and can be adhesively affixed to itself to hold the ring in its assembled position.

Thus, FIGS. 11 and 12 show a drum or container generally designated 110 with an end closure 111. The container 110 will be any conventional type drum or container made of metal or fiber that forms a material receiving chamber generally designated 112 having at least one end opening as at 113. Containers of this type as in the case of the form of the invention shown at FIGS. 1 to 6 of the drawings are well known and easily purchaseable on the open market and hence are not more fully described herein.

The container 110 is provided with an annular bead or contoured section as at 114 which is formed about the end opening 113 of the material receiving chamber 112.

The cover or end closure 111 is received in the opening 113 of the material receiving chamber 112 and includes a central portion 115 and an annular flange 116 connected about the periphery of the central portion 115. The annular flange in cross-section will also have a contoured shape and will be sized to permit the end closure or cover 111 to overlie and mate with the annular bead 114 of the container in assembled position as is clearly shown at FIGS. 11 and 12 of the drawings.

Between the annular bead 114 and annular flange 116 on inner seal 117 is provided.

The inner seal 117 illustrated is the type shown in FIGS. 7 to 10 of the drawings and above described. It will be understood however that the inner seal may be a V-type inner seal such as is shown in FIGS. 1 to 5 of the drawings and above described. It will be understood by those skilled in the art that the selection of one or other of these seals will depend on the particular materials which are to be contained and sealed in the drum and the conditions which have to be met to maintain the security of the end closure assembly.

When the end closure 111 is brought into fluid tight engagement with the annular bead 114 the inner seal will be set in position and when assembled as shown in FIG. 12 will act to prevent leakage or rupture due to hydrostatic pressure from the material or other causes acting in the container 110 during tests, storage or shipment of the container.

The annular flange 116 of end cover 111 is held in engagement with the annular bead 114 of the shipping container 110 by an outer sealing tape 119 and a closure ring 120 which are disposed concentric to each other.

The outer sealing tape will be made of a heat shrinkable material which is adhesively coated or impregnated or which forms a self-adhesive and will be disposed in circumferential engagement with the annular flange 116 and the annular bead 114 when the cover 111 is set into position in the opening 113 and the outer sealing tape being relatively thin may be wound until it overlaps substantially starting end of the tape.

The outer sealing tape 119 as in the case of the form of the invention at FIGS. 1 to 6 above described will be made of a high tensile strength shrinkable plastic mate-

rial and thus when heated and cooled will cause the annular flange 116 of the end closure or cover 111 to be pulled down tightly into mating position on the annular bead 214 of the container or drum 210 and thus flatten and adhesively seat the inner seal 217 in assembled position as is shown in FIG. 12 of the drawings.

Closure ring 120 as shown in FIG. 13 is an elongated member which will be approximately half the thickness of the conventional prior closure ring. This construction gives this type of closure ring considerable pliability so that it can be connected about the outer sealing tape by encircling the end closure elements and the outer sealing tape 119 at least twice or more times and this is facilitated by the semi-circular construction of this element which permits this overlapping to occur uniformly and additionally permits the outer ring of the closure ring to be connected to the inner section of the closure ring by any suitable means such as a pressure sensitive adhesive which can be applied either to the inner wall of the outer lap of the ring or to the outer surface of the adjacent inner lap of the ring which the outer lap will overlie as it is moved into assembled position.

It will be understood by those skilled in the art that other suitable connecting means can be provided for holding this light pliable closure ring in assembled position.

It will at once be apparent that this method of closure is simple and more expeditious than the conventional split ring bolted arrangement as has been above described for the form of the invention shown in FIGS. 1 to 5 of the drawings and similar types of closure rings in the prior art patents referred to above.

This sealing means is thought to be better adapted for meeting the production line speeds and for providing an end closure assembly to meet prices intermediate those which can be met by an end closure assembly simply having heat shrinkable adhesively connected plastic tape for one range of lower pressures and the end closure assembly with the tape and closure ring having lugs and a heavy bolt similar to those used in the prior art which meet the requirements for a range of higher pressures.

CLOSURE RING WITH OVERLAPPING ENDS AND ASSOCIATED LOCKING ELEMENT

The further extension of the end closure assembly with still another form of closure ring is illustrated at FIGS. 14 to 18 of the drawings.

Thus FIG. 14 shows a drum or container generally designated 210 with a cover or end closure 211 contained in 210 may be a metal or fiber type drum such drums are well known and easily purchaseable on the open market similar to those described in the form of the invention shown at FIGS. 1 to 6 of the drawings and FIGS. 11 to 13 of the drawings.

The container or drum 210 will form a material receiving chamber at 212 which will have at least one end opening as at 213. The container or drum 210 is provided with an annular bead or contoured section as at 214 which is formed about end opening 213 of the material receiving chamber 212. The cover or end closure 211 is received in the end opening 213 and includes a central portion 215 and an annular flange 216 connected about the periphery of the central portion 215, the annular flange as shown in cross-section will have a contoured shape and will be sized to permit the end

closure or cover 211 in assembled position overlie and mate with the annular bead 214 of the container all of which is shown in FIGS. 14 and 15 of the drawings.

Between the annular bead 214 and annular flange 216 an inner seal 217 is provided which differs from those above described in that the inner seal comprises a tubular member that has been slit longitudinally on one side and then adhesively fixed to the inner wall of the annular flange 216 of the end closure 211 and to the annular bead 214 of the container 210 in a manner similar to that above described for the tubular element shown in FIGS. 7 to 10 of the drawings.

Thus, as shown in FIG. 15 the inner seal 217 is provided with adhesive means as at 217a for connecting one side of the inner seal to the inner wall of the annular flange 216 and 217b substantially opposite the adhesive means 217a for connecting the inner seal 217 to the annular bead 214 and the slit is positioned so that it faces the inside of the container 210 to communicate with the chamber 212 and thus permit pressure fluid acting therein to pass to the chamber or trap 217d formed by the inner seal 217 when it is in assembled position.

The inner seal will be made of any suitable material which is chemically inert and will resist any erosive or corrosive effect that might occur due to the materials contained in the chamber 212 of the container 210. Plastic materials such as those set forth for the form of the invention described in FIGS. 1 to 5 of the drawings are also suitable and are made in tubular form so that they can provide the gasket of the type above described. The adhesive selected will of course also be resistant to chemical action and such adhesives can also be purchased on the open market.

When the annular flange 216 of the end closure 211 is brought into fluid tight engagement with the annular bead 214 the inner seal will be set in position and will act to prevent leakage from the material receiving chamber 212 formed in the shipping container 210. This is accomplished by an outer sealing tape 219 and a closure ring 220 which are disposed concentric to each other and the closure ring will be sealed or locked in assembled position by a locking element as at 221 more fully described below.

The outer sealing tape 219 is a high tensile strength heat shrinkable plastic material which is adhesively coated or impregnated. Additionally, this tape will have a sufficient width to stretch substantially over the entire annular flange 216 the exposed portion of the annular bead 214 and a portion more or less of the outer wall of the container 210 just below the annular bead 214 as is clearly shown in FIG. 15 of the drawings.

This outer seal 219 will first be applied in circumferential contact with the annular flange 216 the annular bead 214 and the section of the outer surface of the drum 210 adjacent thereto until the ends of the outer seal 219 overlap each other by a substantial amount at least five to ten inches and after the material is positioned it is heated and cooled and this will cause the material to shrink the main direction of shrinking being twice as much in its width as in its length so that in assembled position the shrinkage of the outer sealing tape 219 will cause the annular flange 216 to be pulled down tightly onto the annular bead 214 and flatten therebetween the inner seal 217 as is shown in FIG. 15 of the drawings.

Since the heat shrinkable outer sealing tape 219 includes adhesive either coated thereon or impregnated therein the outer heat shrinkable sealing tape will adhere in assembled position and this form of the end closure will as in the form of the invention shown in FIG. 6 be adapted to seal against predetermined pressures in a range between 3-5 P.S.I.G.

In order to strengthen the heat shrinkable outer seal materials which are reinforced with glass filaments or other types of fibers may be utilized to increase the tensile strength of such outer sealing elements.

However, where the fluid pressures or hydrostatic pressures acting in the container even those applied by tests or those which may arise from the materials in the container or from dents or other mishandling accidents to the container during storage or shipment thereof, exceed the indicated range of 3-5 P.S.I.G. it is necessary to reinforce the outer seal 219 with a suitable closure ring as in the forms of the invention shown in FIGS. 1 to 5, FIGS. 9 and 10 and FIGS. 11 and 12 above described.

Thus, closure ring 220 as shown in FIGS. 14 and 16a is an elongated member which is semi-circular in cross-section. It is pliable in that it is made of relatively light material and will have a lesser thickness than the conventional known prior art type of closure rings which have been above described and which is shown at FIGS. 1 to 5 of the drawings.

The length of the elongated closure ring 220 will be such that it can be easily wrapped circumferentially about the portion of the outer sealing tape 219 in engagement with the annular flange 216 and annular bead 214 and in assembled position the ends will be brought into overlapping position by approximately 5 to 10 inches.

If desired these overlapping sections of the closure ring 220 can be treated with a suitable adhesive to hold the closure ring in assembled position until the locking clamp 221 is affixed and clamped in assembled position to lock the closure ring 220 in the desired degree of overlapping relationship required for the particular end closure assembly on the container 210.

The locking or crimping element 221 is a relatively short member of approximately 5 to 10 inches and will be semicircular in cross-section similar to the shape of the closure ring 220 so that in assembled position it can be brought into snug engagement with the outermost lap of the overlapping portions of the closure ring 220 as is shown in FIGS. 14, 15 and 16b of the drawings. The locking or crimping element 221 will be sufficiently pliable and will have a width such that it can be molded or crimped either manually or automatically about and in engagement with a substantial section of the overlapping portions of the closure ring 220 and this is illustrated by reference to FIGS. 17 and 18. FIG. 17 shows the locking or crimping element before it is clamped in position and FIG. 18 shows the locking or crimping element 221 after it is locked to hold the closure ring in assembled position.

FIG. 16 shows that the locking or crimping element 221 is provided with a pair of spaced ears as at 222a and 222b and 223a and 223b extending respectively opposite edges of the locking or crimping element. These ears are respectively provided with tool receiving openings as at 224a and 224b on the respective ears 222a and 222b and tool receiving openings 225a and 225b on the respective ears 223a and 223b, which will

permit the insertion of a tool such as a screwdriver into such openings to undercrimp or unlock the crimping element after it has been locked in position as shown in FIG. 18 of the drawings and thus permit the end closure assembly to be disassembled quite easily.

On reassembly, the new locking or crimping element will be utilized for reassembling the end closure assembly for the container 210 as has been above described.

Thus, there has been disclosed an end closure arrangement consisting of a combination of inner seal gaskets adhesively connected to the end closure elements for the drum and outer heat shrinkable sealing agent adhesively connected for sealing and setting the adhesively connected seal and where required a shaped closure ring adapted to coact with such combination. This improved end closure assembly will be effective over a far greater range of impending rupture and the conventional prior art form of compressible gasket type end closure assemblies.

It will be understood that the invention is not to be limited to the specific construction or arrangement of parts shown but such parts and arrangement may be widely modified by those skilled in the art within the invention as hereinafter defined in the claims.

What is claimed is:

1. An end closure assembly for a container forming a material receiving chamber with at least one end opening and a rounded section about said end opening comprising:

- an end closure for the container having an annular peripheral element shaped for mating engagement with the rounded section of the container,
- an inner seal adhesively connected between the rounded section of the container and the annular peripheral element on the end closure, and
- an outer sealing means of heat shrinkable material about the container and the end closure in assembled position to form a seal for the end closure assembly by heating and cooling thereof for the required period of time to set the inner seal in assembled position.

2. An end closure assembly as claimed in claim 1 wherein,

- means are provided on the inner seal to form a fluid pressure trap in the inner seal,
- said inner seal having means providing communication between the fluid pressure trap therein and the material receiving chamber in the container, and
- said heat shrinkable outer sealing means adapted to shrink more in the width than the length when heated and cooled to effect setting of the adhesively connected inner seal.

3. An end closure assembly as claimed in claim 2 wherein the inner seal is made of material from the group fluorocarbon resins and polypropylenes.

4. An end closure assembly as claimed in claim 2 wherein the outer heat shrinkable material is made of material from the group fluorocarbon resins and filled fluorocarbon resins, and an adhesive on at least one side of said heat shrinkable material.

5. An end closure assembly as claimed in claim 2 wherein the outer heat shrinkable seal is made of material from the group fluorocarbon resins and filled fluorocarbon resins, and includes an adhesive on at least one face.

6. An end closure assembly as claimed in claim 2 including a closure ring disposed about said heat shrinkable material, and means for locking said closure ring into assembled position to provide a fluid tight end closure assembly.

7. An end closure assembly as claimed in claim 2 including,

- a. a split closure ring means disposed about said heat shrinkable material,
- b. said closure ring means including,
  - 1. a main circumferential section,
  - 2. means forming an overlapping section at one end of said closure ring means disposed to overlap the opposite end in assembled position,
  - c. and means for locking the closure ring in assembled position to form a fluid tight end closure assembly.

8. An end closure assembly as claimed in claim 7 wherein the means for locking the closure ring means in assembled position includes,

- a. a first lug connected to the overlapping means,
- b. a second lug connected medially along the main circumferential section to permit operative connection thereof with the first lug, and
- c. a member including threaded means disposed to connect the first and second lug to each other.

9. An end closure assembly as claimed in claim 8 wherein,

- a. the member having threaded means includes,
  - 1. a hex head at one end,
  - 2. a shank connected at one end to said hex head, and
  - 3. the threaded means is disposed at the end of the shank remote from the hex head,
  - 4. said shank disposed to engage said first lug and said threaded means to extend into said second lug,
  - 5. groove means in said shank to receive an epoxy,
  - 6. an extended threaded section continuous with the threaded means on the member, and
  - 7. means between the threaded means and the extended threaded section to permit the extended section to be separated from the threaded means after the closure ring is assembled.

10. An end closure assembly as claimed in claim 7 wherein said closure ring is hemi-hexagonal in cross-section and includes;

- a. a center section,
- b. spaced side sections connected to said center section,
- c. a first clamping section and a second clamping section connected respectively to opposite side sections at points remote from the center section;
- d. said clamping sections crimped in assembled position,
- e. and means for locking said closure ring means in assembled position.

11. An end closure assembly as claimed in claim 10 wherein the means for locking the closure ring means

in assembled position includes,

- a. a first lug connected to the overlapping means,
- b. a second lug connected medially along the main circumferential section to permit operative connection with the first lug, and
- c. a member having threaded means disposed to connect the first lug and second lug to each other.

12. An end closure assembly as claimed in claim 11 wherein,

- a. the member with threaded means thereon includes,
  - 1. a hexagonal head and a shank continuous with said hexagonal head,
  - 2. the threaded means is connected to the shank means on the side remote from its connection to the hexagonal head,
  - 3. groove means in said shank to receive an epoxy,
  - 4. and an extended threaded section on said threaded means,
  - 5. and means between the threaded means and the extended threaded section to permit the extended threaded section to be separated from the threaded means after the closure ring is assembled.

13. An end closure assembly as claimed in claim 7 wherein,

- a. said overlapping means is disposed to overlap the opposite end in assembled position at least more than once, and
- b. the means for locking the closure ring in assembled position consists of an adhesive connecting the overlapping section to the main circumferential section.

14. An end closure assembly as claimed in claim 7 wherein,

- a. the means forming the overlapping section is relatively short, and
- b. the locking means includes a member disposed to fit about the overlapping portion of the ring and to be crimped in assembled position,
- c. and perforated ears on said locking means to permit disassembly thereof for releasing the closure ring from the locked position.

15. A closing ring for use in an end closure assembly comprising,

- a. a split circumferential element having a length sufficient to permit the opposed ends to overlap each other,
- b. an outer section of said circumferential element having a length to permit the outer section to overlap the inner section of the circumferential element in assembled position at least one entire turn, and
- c. an outer sealing means of heat shrinkable material having adhesive means on one face disposed to engagement with the split circumferential element of the end closure assembly to detachably connect the overlapping section to the overlapped section of the circumferential element.
